Primary Examiner — Catherine S Posthauer(74) *Attorney, Agent, or Firm* — Thedford I. Hitaffer; Hitaffer & Hitaffer, PLLC(57) **CLAIM**

The ornamental design for a spraygun head, as shown and described.

DESCRIPTION

FIG. 1 is a left side, bottom perspective view of a spraygun head, showing my new design;

FIG. 2 is a left side view thereof;

FIG. 3 is a rear, top left side perspective view thereof;

FIG. 4 is a rear, right side perspective view thereof;

FIG. 5 is a top view thereof; and,

FIG. 6 is a front side view thereof.

The broken lines are shown for the purpose of illustrating parts of the article that form no part of the claimed design.

1 Claim, 6 Drawing Sheets

US D1,028,715 S
